GEORGE KING, JOHN GOMBER, AND LYNDHURST T. SHOPE, OF FREDERICK,
MARYLAND.

Letters Patent No. 67,060, dated July 23, 1867.

IMPROVED SASH-FASTENER.

The Schedule referred to in these Letters Patent and making part of the same.

TO ALL WHOM IT MAY CONCERN:

Be it known that we, GEORGE KING, JOHN GOMBER, and LYNDHURST T. SHOPE, of Frederick, in the county of Frederick, and State of Maryland, have invented a new and useful improvement in Sash-Fastener; and we do hereby declare that the following is a full, clear, and exact description thereof, which will enable others skilled in the art to make and use the same, reference being had to the accompanying drawings, forming part of this specification.

The drawing represents a window in section, with our improved device for fastening the sash attached.

This invention relates to a new and improved device for fastening window-sashes, and consists in attaching racks to the sides of the sashes to engage in projecting catches in the frame, by the pressure of springs when the sashes are raised, from which catches the rack-teeth are released by pressure on the sashes, which relieves the springs, as hereinafter more particularly described.

A represents an ordinary window-frame, containing upper and lower sliding-sashes B B. On the inner sides of the sashes, behind the mouldings a a, are fastened metal racks b b, having teeth pointing downwards, which engage in metal catch projections c c, secured to the inside of the window-frame under the moulding. On the outside of the sashes B B are placed springs d d, with rollers on their ends, that are made fast to the mouldings a a, or upon the sashes themselves, and press the sashes inward in such a manner that the rack-teeth shall engage in the catches c c, when the sashes, or either of them, are raised, and thus hold them up at any desired height.

To lower a sash it is only necessary to push against it so as to compress the springs, and thus disengage the rack-teeth from the catches; and for this purpose the sashes fit loosely between the mouldings, with sufficient play for the action and reaction of the springs as described.

Having described our invention, we claim as new, and desire to secure by Letters Patent—

The hooked racks b b, secured to the inner side of the sashes B, behind the moulding a, and held, engaging with the metal projections c, upon the inside of the wooden frame, by means of the springs d d, having rollers, all constructed and described and arranged in such a manner that the sashes shall be pressed outward to raise or lower as herein set forth.

GEORGE KING,
JOHN GOMBER,
LYNDHURST T. SHOPE.
